UNITED STATES PATENT OFFICE.

FRANK OBERST, OF NEW YORK, N. Y., ASSIGNOR TO SONORA PHONOGRAPH COMPANY, INC., A CORPORATION OF NEW YORK.

COMBINATION RADIO AND PHONOGRAPH APPARATUS.

Application filed September 6, 1924. Serial No. 736,232.

This invention relates generally to a combined phonograph and radio receiving set, and more particularly to an instrument in which the phonograph and radio receiving set are contained in the same cabinet, and the employment in such combination of elements capable of and intended for employment in a phonograph construction, and co-ordinately involves either or both, the association with or the attachment to the whole or to a part of a phonograph construction, of mechanism whereby the sound amplifying portions of a phonograph can be employed as a common amplifier for amplifying audio frequency in connection with radio receiving apparatus and for sound reproduction from a phonograph record.

One of the objects of my invention is the construction of a combined phonograph and radio apparatus, utilizing a common amplifier having means to connect or disconnect the radio sound producing means or the phonograph producing means from the said amplifier.

A further object of my invention is to provide a simple, rugged device which will allow the playing and amplification of phonograph sounds in the usual way, without any tone losses, and by an easy manipulation at the will of the operator, the same phonograph horn may be used to amplify a radio reproducer also without tone losses.

Another object of my invention is to provide a device which, when manipulated at the will of the operator, will, by valve action, interrupt the free passage of sound from the phonograph reproducer to the horn, and simultaneously open a free passage for the sound from the radio reproducer and with a manual movement in the opposite direction will produce a reverse simultaneous result.

A further object of my invention is to provide a simple device subject to the will and easy manual control of the operator, whereby the volume of sound issuing from the horn or amplifier, produced either by the phonograph or radio reproducer, may be progressively increased to the maximum ability of either reproducer, or decreased to a mere whisper, or either reproducer may be shut off entirely. All these effects may be secured without any tone losses whatsoever, except such tone losses as are brought about at the express desire of the operator.

One of the objects of the invention is to provide an instrument to produce good sound reproduction of both kinds, and in which the same horn may be used for both purposes.

Another object is to provide an instrument in which the receiving set and the phonograph are compactly arranged in a cabinet of attractive appearance. The combining of these elements is to economize space and to utilize an amplifier for both purposes.

Another object of the invention is to provide an improved combination phonograph and radio, which will be compact, simple in construction, economical to manufacture, efficient in operation, attractive in appearance and inexpensive to manufacture.

With these and other objects in view, to be more fully set forth hereinafter, the invention consists in the novel construction, combination of elements, and arrangement of parts, which will be exemplified in the operation and construction herein described in the following specification and illustrated in the accompanying drawings.

The invention will first be described in connection with the accompanying drawings, wherein similar reference characters are used to designate corresponding parts throughout the several views, and more specifically defined and indicated in the appended claims.

Attention is directed to the drawings in which:

Figure 1 is a front elevation of my invention mounted in a cabinet containing a phonograph and a radio receiving set, with the front panel of the cabinet removed and various parts broken away to show the arrangement of the elements.

Figure 2 is a plan view of the same with the top of the cabinet removed,

Figure 3 is a detail central sectional elevation of my device with the parts in position to give amplification from the phonograph reproducer, and to exclude possible sounds from the radio reproducer.

Figure 4 same as Fig. 3 with the parts in position to give amplification from the radio reproducer to the exclusion of possible sounds from the phonograph reproducer,

Figure 5 is a detail view of my device on the line 5—5 (Fig. 3) looking in the direction of the arrows, and,

Figure 6 is a detail view of my device on the line 6—6 (Fig. 3) also looking in the direction of the arrows.

For purpose of illustration I show my invention mounted in a cabinet 1 divided into radio section 3 and phonograph section 4 by a main vertical partition 2. Radio section 3 is divided by horizontal partition 5 into chamber 6 for the radio receiving set 8 and chamber 7 for the batteries 9 (Figs. 1 and 2). Phonograph section 4 is divided by the horizontal partition 10, commonly called the "motor-board", into chamber 11 and chamber 12. Chamber 11 contains the usual phonograph elements found above the "motor-board", namely tone-arm 13 to which is secured phonograph reproducer 14 adapted to play on record (not shown) placed on turn-table 15. In chamber 12 is housed what I call the sound transfer chamber 16, spring motor box 17 containing the operating parts for turning the phonograph turn-table 15, and crank 18 for winding the motor. Also the amplifier or horn 19 leading from sound transfer chamber 16 to large opening in front of the cabinet as shown. Suspended and fastened to the underside of chamber 16 is a radio reproducer arm 20, the other end of which has secured radio reproducer 21 wired to radio receiving set 8 by suitable wiring (not shown). Passing into chamber 16 is manual control rod 22 to the other end of which is fastened hand button 23 for convenience in manipulating the control rod 22. Having now generally located the elements I will now proceed with a detail description of my invention with particular reference to Figs. 2 to 6. Cabinet 1 has rear panel 24 (Figs. 2, 5 and 6) to which is firmly affixed chamber 16 which is in effect a rectangular box-like structure having bottom 25, sides 26, end 27, ends 28 and with "motor-board" 10 forming the top, which has opening 29 with collar 30 firmly secured therein. Mounted in this collar 30, so as to freely swing in a horizontal plane, in the usual manner, is phonograph tone-arm 13. Adjacent end piece 28 has small opening 31 to permit the passage of control rod 22, while adjacent bottom member 25 has large opening 32 in which is secured the large end of radio reproducer arm 20. Bottom member 25 also has large opening 33 in which is secured the small end of the amplifier or horn 19, as will be readily understood.

Sliding with a close fit in chamber 16 by means of cut out portions 34 (Fig. 6) in sides 26 is a dual-valve member, comprising horizontal slide valve 35, with opening 36 adapted to align with opening 29 as shown in Fig. 3. Secured to slide valve 35 is vertical gate valve 37, having fastened thereto flanged piece 38 firmly anchoring one end of control rod 22. To allow the necessary full horizontal movement of slide valve 35 par-

tition 2 is slotted as at 39. End member 28 serves as a stop to limit the outward movement of the dual-valve, it being understood that any form of stop may be employed such as a wood-screw or small wooden piece for the purpose. If a sound-proof joint is desired, felt or other sound absorbing material (not shown) may be inserted between the upper face of slide valve 35 and the lower face of "motor-board" 10. 75

Gate valve 37 forming one piece with slide valve 35, any manipulation of control rod 22 by means of button 23 will move both valves simultaneously and to the same extent in either direction, as will be readily understood. 80

My device operates as follows. If it is desired to use the phonograph, control rod 22 is pushed as far as possible into the cabinet, by means of button 23. This positions the dual-valve as shown in Fig. 3, and provides a clear, uninterrupted and continuous passage for the phonograph sound through the phonograph tone-arm 13, aligned openings 29 and 36, into the chamber 16, and out through the opening 33 into the horn 19. It will be noticed that with the dual-valve in this position gate valve 37 is closed and offers a practically sound-proof obstruction to keep extraneous sounds arising in the radio reproducer from reaching horn 19, and trapping same in dead space in chamber 16. To modify the volume of phonograph sound it is only necessary to slowly withdraw the control rod 22 from the cabinet, thus moving opening 36 out of line with the opening 29, reducing the orifice 32 the desired degree. 95

In accordance with the provision of the patent statutes, I have described my invention together with the construction which I now consider to represent the best embodiment thereof, but I desire it understood that my invention is not confined to the particular form shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and new results accomplished, as herein set forth; as it is obvious that the particular embodiments herein shown and described are only some of many that can be employed to attain these objects and accomplish these results. 110

Having now described my invention, what I claim and desire to secure by Letters Patent, is:

1. In a sound transfer amplifying device, in combination, a chamber, a dual-valve therein, comprising a slide valve and gate valve, said valves manually operable by a 130

control member, to move simultaneously to cover one opening while uncovering another, and by a reverse movement of said control member, to simultaneously uncover the first 5 named opening while covering the second.

2. In a sound transfer amplifying device, in combination, a chamber, a sliding valve therein, adapted to modify sound from one source, while a gate valve therein excludes 10 from another source, both valves being manually operable simultaneously to produce a reverse result.

3. In a device of the character described, a sound transfer chamber, an amplifier and 15 a pair of sound tubes opening into said chamber, one of said tubes occupying a position spaced from the end walls of said chamber, and a partition for said chamber movable alternatively to either side of said sound 20 tube whereby sound waves from said tube may be alternatively directed toward the amplifier or isolated therefrom.

4. In a device of the character described, a sound transfer chamber, an amplifier and 25 a pair of sound tubes opening into said chamber, one of said tubes opening approximately opposite the amplifier and the other tube opening in a location offset from said amplifier, and a suitable partition slidable 30 in said chamber alternatively from a position beyond said second tube, relative to said amplifier, to a position between said second tube and said amplifier whereby sound waves from said second tube may alternatively have access to said amplifier or be cut 35 off therefrom.

5. In a device of the character described, a rectangular sound transfer chamber, an amplifier opening in one side of said chamber, a sound tube opening in the same side 40 of said chamber, but off-set from said amplifier opening, a second sound tube opening in the opposite wall of said chamber approximately in line with said amplifier opening, and a duplex valve slide of L-shaped cross-section movable in said chamber to alternatively isolate each of said sound tubes 45 from the amplifier.

6. In a device of the character described, a rectangular sound transfer chamber, an amplifier opening in the lower wall of said chamber, a tube entering said chamber through said lower wall and connecting a telephone receiver with said chamber, a second tube opening into the upper wall of said 50 chamber approximately opposite said amplifier opening, said second tube connecting a phonograph tone arm to said chamber, an L-shaped valve slide movable in said chamber, said valve slide having a perforate 55 gate slideable along the top wall of the chamber and an imperforate gate closing an end of the chamber, means by which said valve slide may be moved in said chamber, a movement of said slide in one direction, 60 shutting off said tone arm tube from said chamber, and a movement in the opposite direction isolating said telephone receiver tube from said chamber.

This specification signed this 30th day of 70
August, 1924.

FRANK OBERST.
